UNITED STATES PATENT OFFICE.

ABRAHAM BARRACLOUGH, OF GALLUP, NEW MEXICO.

CAR ARRESTING AND HOLDING DEVICE.

1,281,119.

Specification of Letters Patent.

Patented Oct. 8, 1918.

Application filed February 26, 1918. Serial No. 219,287.

To all whom it may concern:

Be it known that I, ABRAHAM BARRACLOUGH, a citizen of the United States of America, and resident of Gallup, in the 5 county of McKinley and State of New Mexico, have invented certain new and useful Improvements in Car Arresting and Holding Devices, of which the following is a specification.

10 This invention relates to car stopping and holding mechanism and particularly to a device to be used at the bottom of mine shafts where cars are stopped and held temporarily prior to their being delivered to the 15 hoisting cage of a mine.

An object of this invention is to provide novel means for checking the momentum and finally arresting the movement of a car, the said device having novel means for preventing undue shock and vibration owing to the braking action.

20 A further object of this invention is to provide means which might be termed a safety device to be brought into action in 25 case the normal brake or arresting mechanism has proven ineffective and a still further object of the invention is to provide a confining gate to prevent the car from passing into a shaft prior to the descent of the 30 cage so as to avoid accident.

With the foregoing and other objects in view, the invention consists in the details of construction, and in the arrangement and combination of parts to be hereinafter more 35 fully set forth and claimed.

In describing the invention in detail, reference will be had to the accompanying drawings forming part of this specification wherein like characters denote corresponding 40 parts in the several views, and in which—

Figure 1 illustrates a side elevation of a device embodying my invention;

Fig. 2 illustrates an end view thereof;

Fig. 3 illustrates a horizontal section; and

Fig. 4 illustrates a section on the line 4—4 of Fig. 1 with the end wall in elevation.

In these drawings, I have illustrated one embodiment of the invention, although it is 50 to be understood that with respect to certain features, the construction may be modified within certain bounds and this is especially true with relation to the formation of the casing 10 into which a mine car is run. The

55 casing is here shown as being rectangular and the sides as comprising double headed

rails 11 with a sheathing 12 and a lining 13 although, as stated, this may be modified. The side linings 13 preferably project at one end of the casing and are curved as at 14 to 60 create an enlarged opening when the cars enter. The casing has sills 15 on which rails 16 are supported and guards 17 are provided to prevent disengagement of car wheels from the rails.

It is the purpose of the inventor to frictionally engage the sides of the car to break the momentum of the car as it enters the casing and finally to bring it to a stop within the casing prior to its being delivered to a 70 lifting cage or elevator. To that end, I provide a friction device which may be termed a door, the same comprising outer and inner face plates 18 and 19 respectively which incase a filler 20, preferably of wood. 75 The facings may be secured to the filler in any appropriate way as by rivets 21 and the inner facing plate is secured to the side lining 13 by fastenings 22. The so-called gate is free at one end to oscillate and it is held 80 normally inward by a spring 23 whose outer end bears against a head 24 of a rod 25. The rod operates through an aperture 26 of a bracket 26^a and the inner end of the rod is connected to an apertured lug 27 through 85 the medium of a pintle 28, the said apertured lug being connected to the door.

Within the side frame of the casing, there is an aperture 29 for the reception of a screw 30 and the screw 30 is threaded in a bolt 31 90 held in the side frame so that the screw may move into and out of the casing and bear against the door to press it inwardly, the said inward pressure being against the action of the spring 23 so that the door is prevented from swinging too far inwardly by the said spring. The purpose of the inventor is that the door should be in position to engage the side of a car coming into the casing and under normal conditions, the door would 95 yield or spring from the point where the screw 30 engages it and there would be sufficient rigidity of the door to insure friction which would cause the car to brake or come to rest, it being understood that when the 100 car was moved from the casing, the spring 23 would operate to prevent the door from swinging inward beyond the point that it had occupied prior to the entrance of the car.

110 The screw 30 has a hand wheel 31' by which it can be manipulated and a second

screw 32 threaded in a nut 33 near the exit end of the casing has a hand wheel 34 for its operation. The purpose of the screw 32 is to press the end of the gate into the path 5 of travel of a car unyieldingly and thus cause the car to be stopped or held in the casing.

A buffer or stop link 35 has one end hinged as at 36 to one side of the casing and 10 the opposite side of the casing is provided with a tapered pin 37 which enters an eye 38 which eye in the present instance is formed by an extension of the sheathing 12 and bending it on itself to provide an intervening space or eye 38 and the tapered pin 15 is of a size to enter the eye and bear against the link when it is in position to guard the end of the casing. By reason of the fact that the pin is tapered, it can be readily dislodged 20 from the eye without backing the car from engagement with the link as it will only be necessary to tap the lower end of the pin slightly to effect this dislodgment.

As a means for guarding against accidents 25 which might result by reason of a car coming into the casing prior to the replacement of the link or buffer, I have provided a hinged yoke 39 which may swing from the position in which it is shown in Fig. 2 to a 30 position at right angles thereto at the end of the casing so that a car will strike it if the link as stated is not in place.

In the present embodiment of the invention, the yoke is mounted on the pivots 40 35 and 41 and it is provided with a handle 42 which may be manipulated by forcing the handle upwardly to cause the yoke to swing outwardly across the end of the casing.

It will be observed from the foregoing description and from an inspection of the drawing that a number of means are provided for safeguarding the movement of cars and that owing to the presence of the screw 30, the gate may be moved or adjusted 45 to increase or diminish the frictional engage-

ment of the door with a car; that the spring will limit the inward movement of the gate which will allow outward swinging movement thereof; that the screw 32 may be brought into action to hold the gate rigid 50 under certain conditions but which under normal conditions would be threaded out so as to normally disengage the said gate.

The functions and purposes of the combined link and buffer and of the car need not, 55 it is thought, be further described in detail.

I claim—

1. In a car arresting and holding device, a casing, a door having one end secured to the casing and adapted to oscillate with relation to a track, means for exerting pressure on the door intermediate its length, whereby a car beyond the said point of engagement will be yieldingly held and means for yieldingly holding the door in position. 65

2. In a car arresting and holding device, a casing, a door having one end secured to the casing and adapted to oscillate with relation to a track, means for exerting pressure on the door intermediate its length, and 70 means for exerting pressure on the door at a point opposite that at which it is secured to the casing.

3. In a car arresting and holding device, a casing having a track therein, a door yield- 75 ingly held in position to engage a car on the track, a hinged buffer at the end of the casing, a tapered pin engaging the link, and means associated with the casing for holding the pin. 80

4. In a car arresting and holding device, a casing, a yielding door secured to the casing and adapted to engage a car for braking it, a yoke, means for pivotally connecting the yoke at the sides of the casing whereby 85 it may swing across the end of the said casing to arrest a car, and a handle for operating the said yoke.

ABRAHAM BARRACLOUGH.
